UNITED STATES PATENT OFFICE.

BEN VALJEAN, OF SANTA ANA, CALIFORNIA.

PROCESS OF COMBUSTION.

1,280,596.

Specification of Letters Patent.

Patented Oct. 1, 1918.

Continuation in part of application Serial No. 876,847, filed December 12, 1914. This application filed July 12, 1916. Serial No. 108,879.

To all whom it may concern:

Be it known that I, BEN VALJEAN, a citizen of the United States, residing at Santa Ana, in the county of Orange, State of California, have invented new and useful Improvements in Processes of Combustion, of which the following is a specification.

This invention relates to a process of combustion which is applicable to hydrocarbon gases and vapors; and this invention has for its object to provide a process of combustion whereby combustible gases or vapors generated from crude fuels may be burnt in a blue flame, or a luminous flame, or any intermediate type of flame, and whereby this may be done with maximum efficiency and without expenditure of energy to increase the natural draft of the combustion or atomize the fuel from which the supply of gas is obtained. Generally, it is an object of this invention to provide a novel process of combustion in which a higher degree of efficiency is attainable than in processes heretofore practised, and one which may be carried on in an open or unsealed apparatus; and, in the following specification, I point out a previous source of waste and inefficiency in the combustion of gases rich in hydrocarbon, and disclose a general and fundamental improvement in the art of their combustion.

This application is a continuation in part of my application S. N. 876,847, filed December 12, 1914.

For the purpose of explaining my process, I illustrate simple forms of apparatus in the accompanying drawings; but it will be apparent from the following specification that my process is not limited to practice in such forms of apparatus but is adaptable to combustion of gas producing fuels in almost all their uses.

In the drawings Figure 1 is a plan of a preferred form of apparatus for carrying out the process, Fig. 2 is a vertical central section of the same; Fig. 3 is a vertical central section of a modified form of apparatus; and Fig. 4 is a vertical central section of another modified form of apparatus. The drawings show proportional sizes of parts of apparatus successful for certain hydrocarbons; but it will be understood that the sizes and proportions will vary to suit different fuels and different types of flames; all as hereinafter described.

I refer first to Figs. 1 and 2. Therein the numeral 1 denotes a gas supply pipe having branches 1^a and 1^b controlled by valves 2 and 3 respectively to admit gas into chambers 13 and 11. It is immaterial whether the gas is fed through these pipes and valves under pressure or by the draft of the apparatus. At 4 and 5 I provide slide valves for regulating the supply of air through openings 6 and 7, which lead to the chambers 13 and 11, respectively. I provide an inner chamber 8 in which a lean or rich mixture of gas and air of regulable quantity and proportions may be formed by adjustment of the valves 2 and 4. At 9 there is an exit from the chamber 8 which leads to the combustion chamber or chimney 10; to which portion of the apparatus the combustion is limited, for the reason, as hereinafter described, that no explosive mixture is elsewhere formed. The chamber 11 may be filled with pure gas, pure air, or a mixture of gas and air in regulable proportions or quantity, or rate of supply, by the use of the valves 3 and 5. At 12 there is a series of holes for the exit of gases from chamber 11 into a combustion chamber or chimney 10.

By adjustment of the valves 2 and 4, as described, it will be evident that a non-explosive lean mixture of regulable quantities and proportions may be formed in chamber 8 and that it may be burned in the combustion chamber 10 with addition of gas from chamber 11 or with addition of a non-explosive rich mixture of gas and air regulable as to quantity and proportion, which may be formed in chamber 11 in the manner indicated in the foregoing description. For the purpose of most effectually carrying on this operation the chimney 10 may be made somewhat taller. It is most evident that by this apparatus complete control of the mixtures may be exercised, both as to relative quantity and individual proportions, so that a non-explosive lean mixture may be burnt with the addition of a gas or with the addition of a non-explosive rich mixture; and that the proportions and quantities of the various elements may be adjusted to get the results of combustion desired.

In Figs. 3 and 4 I illustrate another means of adjustment for making the change or variation in the preliminary mixtures and thus to control the final result in combustion. In these forms of apparatus the means of

controlling proportions of gas and air in the mixtures resides in the form and size and proportions of various parts of the apparatus rather than in valve control. In both 5 Figs. 3 and 4 numeral 1^a designates the gas supply pipe controlled by the valve 2^a to admit gas in regulable quantities to the upper part of the preliminary mixing chamber 8^a or 8^b. The slide valve 4^a regulates the 10 amount of air which may pass through the air opening 6^a. At 9^a is the entrance to the combustion chamber or chimney 10^a. In either of these cases, as in the other form of apparatus described, combustion begins at 15 9^a except in the case when by the adjustment of the valves 2^a and 4^a, the combustion chamber is filled with a non-explosive rich mixture; and then combustion cannot begin until the mixture reaches the top of the 20 combustion chamber or chimney 10^a. When a rich mixture is not thus formed the supply of gas admitted through the valve 2^a is divided into two parts; one part of the gas is drawn down to or around the jet of air passing 25 upwardly through the opening 6^a and forms therewith a lean mixture; the other part of the gas passes more directly to the entrance 9^a, and into the chimney. Between this lean mixture and the gas there is, of 30 course, a body or film of explosive mixture in which combustion occurs, and the amount of rich mixture of gas that is supplied to the outside of the explosive mixture, depends upon what proportion of the gas is admitted 35 to the foot of the chimney above the level of the explosive mixture and what proportion passes below the level of the explosive mixture to the lean mixture formed by the jet of air passing through the opening 6^a. 40 This division of the gas, as before indicated, depends upon the form, size and shape of the apparatus. The jet of air passing into the much larger chamber 8^b shown in Fig. 4 has much more power to draw a large quantity 45 of gas with it than the jet in the small chamber 8^a of Fig. 3. Consequently the apparatus shown in Fig. 4 draws a larger portion of the gas below the level of the explosive mixture to form a lean mixture with air 50 entering through 6^a. It therefore reserves but a small portion of the gas to form a rich mixture above the explosive mixture. On the other hand, the apparatus shown in Fig. 3 draws but little of the gas below the level 55 of the explosive mixture to form a lean mixture and reserves nearly all of the gas to form the rich mixture above the explosive mixture. It is evident that, by varying the shape and size of preliminary mixing chamber 8^a or 8^b as indicated, a complete control 60 of the results is made possible. That is, I may, by proper proportioning of the apparatus shown in Figs. 3 and 4, burn the combustible gases in a blue, aluminous, or any intermediate type of flame. The pro-

portional sizes of apparatus shown in Figs. 3 and 4 are successful for the following stated cases: I have successfully used in each of these apparatus the gases and vapors given off, by heating, from gasolene, kerosene, and heavier crude oil distillates; fuel oil, and crude oil; and also produce gas made from various solid and liquid fuels; and also natural and artificial fuel gas. With heavy hydrocarbons the apparatus of 70 Fig. 3 is not adapted to produce an entirely blue flame. By an equal opening of valves 2^a and an equal opening of the valves 4^a, of the apparatus of Figs. 3 and 4, respectively, when the larger apparatus produces a blue 75 flame the smaller apparatus produces a luminous flame. If both valves 2^a are opened more (equally) then the larger apparatus produces a luminous flame and the smaller one produces a highly luminous flame. That 80 is, with given feeds of gas and given openings to atmosphere, then the smaller apparatus always draws in less air, forms a larger body of rich mixture, and produces a more luminous or more smoky flame. I have 85 found by trial that it is the proportion of the size of the air inlet opening to the size of the body of gas into which the air enters, and the distance of the air inlet from the similar inlets into the same body of gas, that 90 controls the results as to character of flame. Thus, I find that the large apparatus can produce a blue flame with any of the fuels above noted (of course, the relative openings of the gas and air inlets being regulated 95 differently for each different fuel); whereas the smaller apparatus always, with the same relative regulation of gas and air inlets, produces a more luminous or smoky flame than that produced by the large apparatus. 100 These apparatus are illustrated in correct relative sizes, and in correct relation of size to each other; and the absolute sizes will of course depend upon the amount of combustion desired. 110

The general novel functions of the apparatus herein described (and these are the features of my process) are to form the final explosive or combustible mixture by the intermixture or bringing together of a preliminary formed body which is a non-explosively lean mixture of fuel gas (or vapor) and air and a preliminary body which is non-explosively rich in gas (either a non-explosively rich mixture of gas and air, or gas alone); to prevent combustion until the final mixture by the non-explosibility of the preliminary bodies, and to then precipitate combustion by the act of combining the preliminary bodies to form an explosive 115 mixture; and, for these purposes and the purposes of efficient combustion, to control not only the individual characters of the preliminary bodies (the relative proportions 120 of gas and air therein) but also the relative 125 proportions of the apparatus. 130

volumes of the bodies. The purpose of such formation and control is to control the average mixture in which combustion actually takes place. The utility of controlling the 5 proportions of the explosive mixture in this manner may be clearly shown by the following examples:

For the purpose of illustration I select 10 petrol vapor, as it occupies a somewhat middle position between the heavier vapors that may be used and the lighter gases. For practical purposes the petrol hexane, C_6H_{14} may be taken; a good petrol may, for all 15 practical purposes, be considered as of the formula of hexane, C_6H_{14} , as it is a mixture of this formula with the next lower and higher members of its group in proportions which give about this composition.

The complete combustion of this compound 20 is represented by

Two volumes of this vapor require 19 volumes of oxygen, and as oxygen constitutes 25 20.9 per cent. of the atmosphere, we can take the amount of air required at 90.9 volumes for two volumes of the mixture, or 45.45 volumes of air for each volume of vapor. Petrol vapor begins to be explosive, at atmospheric pressure, when mixed with 20 parts of air; and it ceases to be explosive when mixed with 50 parts of air. If petrol vapor and air are brought together and ignited the initial combustion will be largely 30 limited to a mixture of approximately 1 part of vapor and 20 parts of air, as is shown by the smoke thrown off caused by the initial lack of air to complete the combustion. In other words combustion largely takes 35 place in the richest possible combustible mixture. Again, if a 1 to 20 mixture of petrol vapor and air, for one element, and air, for the other element, be brought together, combustion will occur in an average mixture 40 which must be leaner than one part of gas to 20 parts of air, and in this case the combustion will be highly luminous but smokeless. In either of such cases it will be seen that there is a tendency to burn in a rich 45 mixture which is very far removed from being perfectly combustible (in fact, in the richest mixture possible under the circumstances); and it is this tendency, with its accompanying inefficiency of combustion, 50 which my process avoids by the use of a lean mixture. In other words, instead of approaching combustibility from the rich side, the mixture in my process approaches combustibility from the lean side.

55 If a non-explosive lean mixture, which we have seen to be 1 part vapor to 50 or more parts air under atmospheric pressure, be brought together with a mixture of 1 part petrol vapor to 20 or less parts air, and the 60 two ignited, I have found that combustion

will take place on the average in a much leaner mixture than in the one previously mentioned; that is, in a mixture much leaner than the 1 to 20 mixture; and the average leanness of the mixture in which combustion 70 takes place will depend upon the proportions relative and individual of the two mixtures brought together. The experimental evidence of this fact is found in the gradual loss of luminosity of the flame as the proportionate amount of lean mixture formed before combustion is increased.

Finally, if a 1 to 50 mixture of petrol vapor and air is quickly mixed with 1/510th of its volume of petrol vapor, the proportions 80 will be very closely correct for the complete combustion of the lean mixture. The combustion of the vapor mixed in the lean mixture, or the combustion of the rich mixture formed of that vapor, will not be manifest 85 but all combustion will appear to take place in the lean mixture. The flame is almost invisible and the average mixture in which combustion initiates itself and takes place must obviously be very close to a perfectly 90 combustible mixture, because the original lean mixture was not very far from being perfectly combustible. Where the final explosive or complete combustible mixture is formed in this manner, or in the very nearly 95 analogous manner of mixing a rich mixture with a lean mixture which is very nearly explosive, the combustion may readily be made to take place in the lean mixture exclusively, for the same reason that when vapor and air 100 are brought together combustion takes place in the rich mixture exclusively.

I have found that similar results may be obtained from other hydrocarbon gases and other hydrocarbon vapors, the individual 105 and relative proportions of the mixtures depending of course upon the chemical compositions and the range of combustible mixtures of the fuel being used; and it will be seen from the foregoing specification that 110 it is a result of this method or process to carry on a combustion in a mixture much more nearly perfectly combustible than has heretofore been possible in open flames, as, for instance the burning of gas in air in any 115 of the ordinary manners. This is because of the fact that in my process the preliminary mixture or mixtures may be brought to a state very closely bordering on combustibility; and then, when the final mixture is 120 made, combustion takes place in a final mixture much more perfectly combustible than in the ordinary case.

Having described a preferred form of invention, I claim:

1. The process of combustion consisting of 125 forming a non-explosive lean mixture of gaseous fuel and air, forming a non-explosive rich mixture of gaseous fuel and air, bringing said mixtures together, burning 130

- said mixtures, and regulating the relative proportions of said mixtures to form a blue, luminous, or intermediate type of flame as desired.
- 5 2. The process of combustion consisting of forming a non-explosive preliminary body which is a lean mixture of gaseous fuel and air, forming another preliminary body which is non-explosively rich in gaseous fuel, bringing the two bodies together, burning the bodies, and regulating the relative volumes of said bodies and the relative proportions of the constituents of each body, to form a blue, luminous or intermediate type of flame as desired. 20
- 10 15 3. The process of combustion consisting of forming a non-explosive preliminary body which is a lean mixture of gaseous fuel and air, forming another preliminary body which is non-explosively rich in gaseous fuel, bringing the two bodies together, burning the bodies, and regulating the relative volumes of said bodies and the relative proportions of the constituents of each body, to form a blue, luminous or intermediate type of flame as desired. 25
- 15 3. The process of combustion consisting of forming a non-explosive preliminary body which is a lean mixture of gaseous fuel and air, forming another preliminary body which is non-explosively rich in gaseous fuel, bringing the two bodies together, burning the bodies, and regulating the relative volumes of said bodies and the relative proportions of the constituents of each body, to form a blue, luminous or intermediate type of flame as desired.

which is a lean mixture of gaseous fuel and air, forming another preliminary body which is non-explosively rich in gaseous fuel, bringing the two bodies together, burning the bodies, and regulating the relative volumes of said bodies and the relative proportions of the constituents of each body, to form a blue, luminous or intermediate type of flame as desired.

In witness that I claim the foregoing, I have hereunto subscribed my name this 5th day of July, 1916.

BEN VALJEAN.
